UNITED STATES PATENT OFFICE

2,362,076

BUFFING MACHINE

Norwood H. Knowlton, Rockport, Mass., assignor
to United Shoe Machinery Corporation, Flem-
ington, N. J., a corporation of New Jersey

Application September 8, 1943, Serial No. 501,551

8 Claims. (Cl. 51—76)

This invention relates to buffing machines, and is herein illustrated and described as embodied in a buffing machine of the type disclosed in United States Letters Patent No. 2,218,537, granted October 22, 1940, upon my application. The illustrated machine, like that disclosed in said Letters Patent, is adapted to the buffing of soles prior to their attachment to shoes. Both machines are similar to the extent that they utilize a plurality of feed belts which are driven in a direction oblique to the buffing roll. The obliquity of the feed belts imparts to the work a feeding movement having a component which is endwise with respect to the buffing roll, and because of this endwise component the various particles of grit upon the buffing roll will engage the work piece at different localities endwise of the roll, or transversely of the work piece, upon successive rotations of the roll. Any tendency of exceptionally large particles of grit to make visible scratch marks upon the surface of the work, will thus be avoided.

An object of the present invention is to provide a machine of the type under consideration which is simple and which is well adapted to operate upon work pieces which have marked differences of thicknesses transversely of the direction of feed. In accordance with a feature of this invention, the illustrated machine is provided with a plurality of independently yieldable pressers engageable with the respective feed belts for causing the belts to press the work piece against the buffing roll. Since these pressers are yieldable independently of each other they can accommodate work pieces having considerable variations in thickness, such as relatively thick soles which are skived to a feather edge. The pressers, herein illustrated, consist of individual pulleys for the feed belts, together with resilient means for independently pressing each pulley toward the buffing roll to hold the work piece against the buffing roll, all of which pulleys have their axes parallel to each other and oblique to the axis of the buffing roll.

These and other features of the invention will appear more fully from the following detailed description when read in connection with the accompanying drawings, and will be pointed out in the appended claims.

Referring to the accompanying drawings,

Fig. 1 is a view in front elevation of a machine in which the invention is embodied;

Fig. 2 is a view in side elevation of the machine shown in Fig. 1;

Fig. 3 is a plan view of the machine omitting

certain parts such as the dust hood to show the relation of the feed belts to the buffing roll and the cleaning brush;

Fig. 4 is a plan view similar to Fig. 3 but omitting also the buffing roll and portions of the feed belts to show the belt support pulleys;

Fig. 5 is a section taken on the line V—V of Fig. 4 showing one of the belt supporting pulley units;

Fig. 6 is a sectional view taken on the line VI—VI of Fig. 5; and

Fig. 7 is a detail in side elevation of one of the shaft supports.

The operating instrumentalities of the illustrated machine comprise a buffing roll 10, a feed mechanism 12, and a cleaning brush 14 all mounted in the upper portion of a frame 16. A work table 17 facilitates the introduction of work pieces by the operator to the feed mechanism.

The buffing roll, which may be similar to that disclosed in United States Letters Patent No. 2,218,538, granted October 22, 1940, in my name, is carried by a shaft 18 (Fig. 3) journaled in bearings 20 secured upon shelves 22 which are a part of the frame. The cleaning brush 14 has a wooden hub 24, one end of which is secured by set screws in a socket 26 carried by a spindle 28. The other end of the brush 14 is similarly secured in a socket 30 carried by a spindle (not shown). The spindle 28 is journaled in a bearing (not shown) secured to the under surface of the horizontal flange of an angle bracket 32 which is carried by a pair of vertical posts 34 and 36. The bearing for the spindle at the opposite end of the brush 14 is secured to the under surface of the horizontal flange of an angle bracket 38 which is secured to a vertical post 40. The posts 34, 36 and 40 all extend upwardly and are all secured to a vertical plate 42, which, in turn, is carried by a pair of upwardly extending posts 44 and 46 secured to vertical surfaces on the sides of the bearings 20 respectively. The axes of the buffing roll and the cleaning brush are horizontal and parallel to each other, and are inclined at an angle of 15° to the transverse center line of the machine.

The feed mechanism 12 comprises a plurality of parallel feed belts 47 which are composed of a resilient rubber composition material and may be of the type disclosed in United States Letters Patent No. 1,662,511, granted March 13, 1928, on the application of Walter Geist. These belts extend forwardly and rearwardly of the machine, at right angles to the transverse center line and with both the upper and the lower runs of the

belts substantially horizontal. The forward portions of the belts run in the grooves of a common pulley 48 (Figs. 3 and 4) and the rear portions of the belts run in the grooves of a common pulley 50. The pulley 48 is mounted for free rotation upon a stationary shaft 52 which is secured at one of its ends by a pair of set screws 54 and 56 (see also Fig. 7). A similar pair of set screws, also numbered 54 and 56, are provided for securing the other end of the shaft. The set screws 54 and 56 of each pair are coaxial, and with reference to the shaft 52 are in diametrically opposed relation to each other, extending forwardly and rearwardly with respect to the machine. They are threaded through upstanding ears 58 and 60 of a bracket 62 which in turn is secured by screws 64 for heightwise adjustment upon a standard 66 secured upon a shelf 68 of the frame 16. It is evident that each end of the shaft 52 can be adjusted forwardly or rearwardly by loosening one of the screws 54 or 56 and tightening the other. The pulley 50 is mounted for free rotation upon a stationary shaft 70 which is secured at its ends for adjustment forwardly or rearwardly and also for heightwise adjustment by bracket assemblies 72 similar to the bracket assembly comprising the members 66 and 62 and the set screws 54 and 56 already referred to. Also mounted on the pulley 50 is a sprocket-wheel 74 (Fig. 4) over which runs a chain 76 (Figs. 3, 1 and 2) for driving the pulley. The shelf 68 has an opening to accommodate the chain 76.

The feed belts are supported at the locality of operation, and are urged upwardly to press a work piece yieldingly against the buffering roll, by a mechanism comprising a plurality of idler rolls or pulleys 78 (Figs. 2, 4, 5 and 6). Each of the pulleys 78 supports one of the belts 47 and is in turn carried by an upstanding plunger 80. The plungers 80 are all slidably mounted for heightwise movement independently of each other in a frame 82 (which, together with the pulleys 78 and the plungers 80, will presently be described more in detail) and each plunger is urged upwardly by a compression spring 84. The frame 82 is secured at each of its ends by a clamping screw 86 to an upwardly extending flange of an L-shaped bracket 88. The clamping screws 86 extend through heightwise slots in the brackets 88 to provide for heightwise adjustment of the supporting frame 82. Such heightwise adjustment is facilitated by screws 90 threaded through ears extending from the supporting frame and having their ends abutting the edge of the upstanding flange of the bracket 88. Each of the brackets 88 has also a horizontal flange which is pivotally mounted for limited tilting movement upon a fulcrum pin 92 having a horizontal axis extending transversely of the machine. Each of the pins 92 is carried by a stud 94 secured in the shelf 68. The frame 82 may be clamped in any desired position of tilting adjustment about the fulcrum pins 92 by a rod 96 having one end pivotally connected to the frame 82 and having its other end in threaded engagement with a nut 98 (Figs. 1, 2 and 3). The rod 96 passes through a hole in a plate 100 secured to the frame 16, and the outer surface of this plate serves as an abutment for the nut 98. A coil compression spring 102 surrounding the rod 96 is interposed between the inner surface of the plate 100 and a collar 103 on the rod 96. The spring 102 urges the rod 96 as far to the right (as seen in Fig. 2) as is permitted by the nut 98. It is evident that

turning of the nut 98 will move the rod 96 longitudinally and thereby adjust the rolls 78 forwardly or rearwardly. The purpose of this adjustment will be explained later.

5 The frame 82, as shown in Fig. 4, extends obliquely across the feed belts, and the line joining the centers of the pulleys 78 is parallel to the axis of the buffering roll 10. The frame 82 comprises a pair of parallel vertical plates 104 and 106 spaced at their ends by blocks 108 and 110 and secured together at their ends by screws 112 (Figs. 4 and 5). The plungers 80 are guided for heightwise movement between the plates 104 and 106 and are supported laterally by sliding 15 contact with each other, except that the end plungers are supported laterally on their outer surfaces by the respective spacer blocks 108 and 110. These plungers, except for their upper portions, appear in cross section as oblique parallelograms, as shown in Fig. 4. The upper portion of each plunger is notched to leave an upstanding side flange 114 and to provide a space for the pulley 78 which the plunger supports. Secured in each flange 114 is a horizontal, laterally extending pin 116 (Fig. 6) which constitutes a bearing upon which the pulley rotates. One face of each pulley is thus adjacent to its supporting flange 114, and the opposite face is adjacent to and in sliding contact with the supporting flange of the 20 neighboring pulley. The pins 116 are all parallel to each other, extending transversely with respect to the feed belts; but they are offset in the direction of feed to bring the line of centers of the pulleys parallel to the axis of the buffering roll 25 10. The plate 104 has a lug 118 at each end by which the supporting frame 82 is clamped to the brackets 88. The pivotal connection between the rod 96 and the frame 82 is carried by the spacer block 110.

30 40 Each of the plungers 80 rests upon a collar 120 formed upon the upper portion of a pin 122. The pins extend upwardly a short distance above the collars 120 and engage sockets formed in the bases of their respective plungers to keep the pins centered. Each pin 122 is surrounded by one of the springs 84, the upper end of which bears against the collar 120 and the lower end of which bears against a common abutment in the form of a shelf 126 having holes through which the pins extend to permit downward movement of the plungers when the springs are compressed. Upward movement of the plungers under the influence of said springs is limited by a flange 128 extending from the inner wall of the plate 106 and engaging a vertical slot 130 in each of the plungers 80. The slots 130 are long enough to permit sufficient freedom of downward yielding to the plungers.

45 50 55 60 65 70 75 The effective stress of the springs 84 may readily be varied by adjustment. To this end the shelf 126 is provided with a supporting flange 132 (Fig. 6) which extends upwardly in contact with the outer wall of the plate 106. Extending outwardly from the top of the flange 132 is a horizontal flange 134 which rests upon the upper edge of a long plate-like adjusting bar 136. The inner face of the bar 136 is adjacent to the outer face of the flange 132. Secured to the plate 106 by screws 138 is a retaining plate 140 which is maintained parallel to the plate 106 by spacing washers 142 on the screws 138. The supporting flange 132 and the bar 136 are slideable between the plate 106 and the retaining plate 140, the supporting flange being restricted to vertical

movement by the engagement of its vertical edges with the spacing washers 142. The lower edge of the bar 136 has two inclined cam portions 144 (Fig. 5) which are in stepped relation to each other and which bear respectively against the spacing washers 142 of the two upper screws 138. If desired, anti-friction rolls may be mounted on the washers. It is evident that movement of the bar 136 to the left will cause the bar to ride up on the washers and to raise the supporting flange 132, thereby increasing the stress of the springs 84, while movement of the bar to the right will result in a slackening of the stress of the springs. For the convenience of the operator in performing this adjustment a finger hole 146 is provided in the bar 136.

In order to insure the proper presentation of a work piece to the buffing roll, and the control of the feed of the work piece by the belts 47, there is provided a presser plate or, as it is more usually called, a throat plate 148 (Figs. 1, 2 and 3) which inclines downwardly from the front of the machine and has its forward lower edge beveled as indicated by the reference numeral 150 on Fig. 2. The throat plate is parallel to the axis of the buffing roll, and its lower edge is also parallel. The throat plate is clamped against an inclined surface on a cross member 152 extending obliquely across the frame 16 in a direction parallel to the axis of the buffing roll 10. Clamping bolts 154 (Fig. 1) threaded into the cross piece 152 and extending through slots 156 in the throat plate 148 provide for securing the throat plate in any desired position of adjustment along the direction of downward inclination of the throat plate to bring the plane of the bevel 150 slightly secant to the periphery of the buffing roll. A keyway 158 on the throat plate extending in a direction at right angles (as seen in horizontal projection) to the axis of the buffing roll and engaging a key on the cross piece 152 holds the throat plate against movement transverse to the direction of its adjustment. The cross piece 152 is secured at its end to the shelves 22 by clamping bolts 160 threaded into the shelves 22 and extending through slots in the cross piece to enable the cross piece to be adjusted in a direction which is horizontal and at right angles to the axis of the buffing roll.

The supporting pulleys 78 should engage the feed belts at a locality which lies between the beveled edge 150 and the line of tangency between the work piece and the buffing roll. The upward pressure of the work piece caused by the springs 84 is thus distributed between the beveled edge 150 of the throat plate and the buffing roll. To keep the rapidly rotating buffing roll from taking control of the feed, the greater part of the pressure exerted by the work piece should be against the beveled edge 150. The upper surface of the work piece, which is to be presented to the buffing roll, will be held flat by the beveled edge 150, and any irregularities of transverse thickness, such as may result from skiving, will be taken up by the differential yielding of the springs 84. The upper surface of the work piece will therefore be presented flat (transversely) to the buffing roll and with substantially uniform pressure along its entire width notwithstanding variations in transverse thickness. The purpose of the tilting adjustment of the frame 82 effected by the nut 98, is to enable the locality of operation of the supporting rolls to be adjusted forwardly or rearwardly to obtain a more desirable

balance of pressure between the buffing roll and the throat plate.

Additional support for the feed belts 47 at the locality of the brush 14 is provided by a plurality of idler pulleys 162 which are each urged upward independently of the others by a mechanism 163 similar to that already described for the pulleys 78. A throat plate 164 carried by the posts 40 and 34 and having a beveled edge 166 engages the upper surface of the work piece in advance of the brush 14 and cooperates with the pulleys 162 in presenting the work to the brush. No provision for forward and backward adjustment of the pulleys 162 is necessary.

For driving the various instrumentalities above described, there is provided a motor 168 (Figs. 1 and 2) housed in the lower portion of the frame 16. A belt 170 driven by a pulley on the shaft of the motor 168 passes over a pulley 172 and another pulley 174. The pulley 174 through gearing 176 drives a sprocket wheel 177 which in turn through the sprocket chain 76 drives the sprocket-wheel 74 on the feed belt pulley 50. The brush 14 is driven by a belt 178 passing over a second groove in the pulley 172 and over a pulley 180 on the brush spindle 28. The buffing roll is provided with a pulley 182 secured on the shaft 18 and driven by a belt 184 which passes over a pulley 186 in the lower portion of the frame 16. Running over a second groove in the pulley 186 for driving the belt 184 is a belt 188 passing over a pulley on the shaft of the motor 168. The pulley 186 is freely rotatable upon a shaft 190 which is carried by a bracket 192 clamped by a screw 194 against a pair of finished surfaces 196 extending inwardly from the side wall of the frame 16. A slot 198 in the bracket 192 enables the bracket to be adjusted longitudinally or angularly about the screw 194. A similar support 200 is provided for the pulley 172.

For removing dust resulting from the operation of the buffing tool and the brush there is provided a dust hood 202 (Figs. 1 and 2) mounted on the plate 42 and connected to a suction intake 204 of the usual dust disposal system. The lower edge of the plate 42 is close to the buffing roll 10 to enable the plate to serve as a baffle. An opening, however, is provided in the plate to enable the suction of the intake 204 to reach the forward portion of the hood.

The operation of the machine will be apparent from the foregoing description. A work piece such as a skived sole is advanced along the feed table 17 by the operator until it reaches the feed belts 47, whereupon the work piece is carried by these belts to a locality at which it is gripped between the supporting rolls 78 and the beveled surface 150 of the throat plate. The pressure of the work piece against the surface 150 enables the feed belts 47 to control the feed of the work piece notwithstanding the fact that the buffing roll 10 with its rough surface is rotating at a much higher speed than the feed belts are advancing. A portion, depending on the adjustment of the rod 96, of the pressure exerted by the presser rolls holds the work against the buffing roll. Because each supporting roll 78 is provided with its individual spring 84, these rolls may yield independently of each other to accommodate variations of the thickness of the work piece laterally and thereby to cause the work piece to bear with substantially uniform pressure against the buffing roll notwithstanding such variations of thickness. Because of the angular relation between the axis of the buffing roll and

the transverse center line of the machine, the path of travel of each point on the buffing roll will be inclined to the direction of feed of the work. Each particle of grit on the rapidly rotating buffing roll will therefore, on each succeeding rotation of the roll, engage the work along a line slightly displaced laterally from the line of engagement of the previous rotation. The effect of any irregularity in size or sharpness of the particles of grit on the buffing roll will thus be distributed over the surface of the work piece rather than confined to a relatively few conspicuous scratch marks. The work pieces, before dropping from the delivery end of the belts 47, are engaged by the brush 14 which frees them of dust.

Having thus described my invention what I claim as new and desire to secure by Letters Patent of the United States is:

1. A buffing machine, comprising a buffing roll, flexible work-feeding means driven in a direction oblique to the axis of said buffing roll, and a plurality of individually yieldable members engaging and acting through said work-feeding means along a line parallel to the axis of said buffing roll for causing the work-feeding means to press the work against the buffing roll.

2. A buffing machine, comprising a buffing roll, a work-feeding mechanism having driven endless belting upon which the work is carried past said buffing roll, the axis of said buffing roll being disposed obliquely to the direction of feed of said belting, and a plurality of individually yieldable resiliently actuated members engaging said belting along a line parallel to the axis of said buffing roll for causing the belting to press the work against the buffing roll.

3. A buffing machine, comprising a driven buffing roll, a plurality of driven feed belts for feeding work past the buffing roll, and a yieldable member associated with each belt and acting through its associated belt independently of the other yieldable members to press the work against the buffing roll.

4. A buffing machine, comprising a driven buffing roll, a plurality of driven feed belts extending obliquely to said buffing roll for feeding work past the buffing roll, and a resilient means associated with each belt for causing the belts to press a work piece against the buffing roll, each resilient means being yieldable independently of the others

to accommodate local variations in thickness of the work piece.

5. A buffing machine, comprising a buffing roll, a plurality of driven parallel feed belts oblique to said buffing roll for feeding work past the buffing roll, a pulley for supporting said belts at a locality in advance of the buffing roll, and a pulley for supporting said belts at a locality to the rear of said buffing roll.

10 6. A buffing machine, comprising a buffing roll, a plurality of parallel feed belts oblique to said buffing roll for feeding work past the buffing roll, a pulley for supporting said belts at a locality in advance of the buffing roll, a pulley for supporting said belts at a locality to the rear of said buffing roll, means for driving one of said pulleys, and means for pressing the feed belts upwardly to cause them to press a work piece against the buffing roll.

20 7. A buffing machine, comprising a buffing roll engageable with one surface of a work piece of sheet material, a plurality of driven parallel feed belts for feeding work past the buffing roll, a pulley for supporting said belts at a locality in advance of the buffing roll, a pulley for supporting said belts at a locality to the rear of said buffing roll, an individual pulley for each of said belts for supporting its associated belt in the vicinity of said buffing roll, and resilient means for independently pressing said individual supporting pulleys toward the buffing roll to hold a work piece on the feed belts against the buffing roll.

25 8. A buffing machine, comprising a plurality of driven parallel belts having their upper runs substantially horizontal for feeding a work piece, a buffing roll extending across the path of a work piece on said feed belts for buffing the exposed surface of the work piece, a brush extending across the path of the work piece on said feed belts for cleaning the exposed surface of the work piece after the work piece has been engaged by said buffing roll, a throat plate in advance of the buffing roll, a second throat plate in advance of the brush, a row of spring-pressed members for exerting pressure through the belts to hold the work piece against the first throat plate and the buffing roll, and a second row of spring-pressed members for exerting pressure through the belts to hold the work piece against the second throat plate and the brush.

NORWOOD H. KNOWLTON.
